UNITED STATES PATENT OFFICE.

ORLANDO FULLER BELCHER, OF WINTHROP, MASSACHUSETTS.

CARTRIDGE-LOADING MACHINE.

SPECIFICATION forming part of Letters Patent No. 336,689, dated February 23, 1886.

Application filed October 23, 1885. Serial No. 180,731. (No model.)

To all whom it may concern:

Be it known that I, ORLANDO FULLER BELCHER, a citizen of the United States, residing at Winthrop, in the county of Suffolk 5 and State of Massachusetts, have invented certain new and useful Improvements in Cartridge-Loading Machines; and I do hereby declare the following to be a full, clear, and exact description of the invention, such as will 10 enable others skilled in the art to which it appertains to make and use the same, reference being had to the accompanying drawings, and to letters or figures of reference marked thereon, which form a part of this 15 specification.

This invention relates to "cartridge-loading" machines, so called, and may be considered as an improvement on the invention embodied in Letters Patent of the United States No. 20 305,136 issued to myself on the 16th day of September, 1884.

My improvements consist in the peculiar mechanical arrangement of parts, which may be adapted for or applied to any kind of a cartridge-loading machine in which the movable gate or gates operating to admit powder or shot to the empty cartridge are connected with and controlled upon the wad-rammer lever or handle. The peculiar advantages 30 arising therefrom being economy in time, and thus greater rapidity in the act of loading, since the right hand, which is generally employed in actuating the rammer-handle, is not removed therefrom during the filling of a cartridge, but controls not only the admission of both powder and shot but likewise the insertion of the wads, each of such acts being accomplished independently of each other and at the will of the operator.

40 In the accompanying drawings, Figure 1 represents a front elevation of a machine for loading cartridges, in which the operative parts are shown in their positions just prior to the introduction and filling of a cartridge, 45 while Fig. 2 shows a similar view, with the lever and the actuating-gate mechanism in the position just after delivering the powder, but prior to the insertion of the wad upon the latter. Fig. 3 is a modification.

50 Since the general features of the cartridge-loading machine herein shown are embodied

and fully described in the above-mentioned Letters Patent, it will be unnecessary to describe them in detail, and reference to such parts will accordingly be very brief and general.

In said drawings the frame of the machine, adapted to be clamped to any suitable table or bench, is represented at A as surmounted with a hollow gate-containing chamber, B, in 60 which the gate *a* reciprocates. This gate controls both the discharge-passages leading from the powder and shot hoppers, (shown respectively at C D.) These latter are secured to the circular bosses cast upon the chamber B. 65

At E is represented a passage or duct, which is common to both hoppers, and alternately conveys powder or shot to the cartridge contained within and supported by the cartridge-holder F. Furthermore, a horizontal table or shelf is provided at G, (constituting part of the frame A,) and formed with a slight rim or upraised edge, by means of which the wads to be inserted in the cartridges are maintained upon the shelf. Firmly secured to this shelf 70 is an upright post or standard, *b*, to the upper end of which is pivoted an oscillating arm or lever, *c*. This latter extends loosely through an eye or socket, *d*, formed in the upper extremity of the wad-rammer or plunger *e*. 80 This plunger, spring-actuated, is reciprocated by means of the lever *c*, and plays vertically through an extension or boss, *s*, formed upon or attached to the frame A.

Now, in my invention before referred to, 85 the operation of driving home a wad and of admitting shot or powder to the cartridge then in process of loading, was effected by two distinct levers disconnected. Consequently a shifting or change in the position of the hands was 90 required, attendant with much loss of time, and I have herein endeavored to obviate this difficulty by a combination of parts, which enable the operator to maintain his right hand continuously upon the lever *c*, to actuate the 95 rammer *e*, and yet with the same hand be enabled to likewise operate the mechanism serving to open and close the gates admitting either powder or shot. Thus either of the latter may be admitted at will into the cartridge, and at 100 the same time the plunger is actuated to drive home a wad, as circumstances require in the

process of loading, each of the above acts being independent of the other.

To secure the above results I have pivoted to the shelf G, provided for the wads, a vertically-disposed arm, f, which is furnished with two laterally-projecting rods, g h, pivoted thereto. The former one, g, is located about centrally of the arm f, and extends to and is connected with a stud, i, projecting from the gate a, which controls the flow of powder and shot, while beyond, at the extremity of the arm f, I have secured the other rod, h, which is attached to a metallic sleeve, H, movable upon the lever-handle c. From the disposition of these various parts it will be readily perceived that the independent pivotal attachment of the actuating gate-rod h, enables the lever c to descend in the act of driving a wad and then return without effecting any change in the position of the cut-off gate. On the other hand, when movement of the gate is desired, a slight thrust of the hand which always grasps the movable sleeve H enables a charge of powder or shot to be quickly admitted, dependent upon the motion in which the sleeve is directed upon the lever; and this result may be accomplished without moving the lever c.

The operation of the machine containing the mechanism above described, and which embodies my invention, is as follows, premising that the various operative parts are in the positions, as shown in Fig. 1, with the wad-rammer upraised and with it the lever c, while the sleeve H, actuating the gate-rods g h, is drawn away from the extremity of the lever-handle c. Now, supposing an empty shell has been inserted in the cartridge-holder F. The next step is to admit powder, when the operator with his right hand grasps the movable sleeve H and thrusts it out toward the extremity of the lever c. This movement rocks the upright arm f and directs the gate a toward the hopper D, as shown in the dotted lines, thereby permitting flow of powder from the opposite hopper, C. Simultaneously therewith a wad or wads are inserted with the left hand within the mouth of the cartridge-holder; and a second motion or pull of the right hand compels the plunger e and lever c to advance downward, when the wad is forced home. This descent of the lever c has carried with it the rod h and movable sleeve H into the position shown by dotted lines in Fig. 1, the gate-rod g remaining stationary, since the other rod, h, pivots upon the arm f, and no motion of the latter occurs. The wad being driven down upon the powder, the operator permits the plunger to rise by the action of its spring, and when said plunger has withdrawn from the shell he again thrusts the movable sleeve H in direction of arrow 1. (See Fig. 2.) This action effects an opposite rocking of the arm f to that previously accomplished, and a similar but reverse swing 65 ing of the gate a is produced when shot is admitted to the cartridge. Then, without changing the position of his right hand after the in-

troduction of a wad with his left, he pulls the lever c down and the second wad is driven into its proper place. The cartridge is now 70 completely loaded, and only requires to be crimped before being removed. Upon the driving of the last wad, the wad-rammer is permitted to return to its normal or raised position, carrying the movable sleeve H, which 75 remains inactive or unmoved theron, and thus the parts will be seen to have resumed the positions shown by the full lines in Fig. 1, and ready for the insertion and loading of a fresh empty cartridge.

It is a well-understood principle in the proper loading of cartridges that it is very necessary to drive the powder down hard. Consequently the wad upon the latter must be forced down with more force than the wad 80 resting upon the shot. Moreover, it will be noticed in the operation of loading that the act of opening the gate to admit powder brings the sleeve H out upon the extremity of the lever actuating the wad-plunger; hence greater 85 power is obtained at the right time or at the moment the wad upon the powder is to be driven home. On the other hand, admission of the shot causes the sleeve to be withdrawn from the end of the lever, thereby shortening 90 the latter and diminishing the power of said lever.

It is very evident that various modifications may be adopted by which to accomplish the result produced by the sleeve H herein shown, 100 and yet not depart from the spirit of my invention, which I consider consists in a gate-operating mechanism connected with the wad-rammer lever of a cartridge-loading machine, whereby without removal of the hand from 105 said lever shot or powder may be admitted to the cartridge, or wads inserted therein, each of such acts being accomplished separately and independently one of the other at the will of the operator.

Upon reference to Fig. 3 of the drawings, which represents a modification of the machine, it will be observed that the vertical arm f is omitted and the two actuating gate-arms, g h, are pivotally united together. Furthermore, I have formed a slotted boss, j, upon the post b, and through which the lower rod, g, passes, while a small roller, k, is secured in said slot to support said rod, lessen the friction, and thereby enable said rod g to slide more 120 freely in the act of reciprocating the gate a.

claim—

1. In combination with the measuring-gate and loading-plunger of a cartridge-loading machine, a lever, c, actuating said plunger, a sleeve, H, sliding on said lever to operate the gate, and mechanism connecting said sleeve to said gate, substantially as stated.

2. The plunger e, having a slotted head, d, in combination with an operating-lever, c, which passes through said slot, and connections between said lever and the measuring gate, substantially as set forth.

3. In combination with the measuring-gate

and plunger, the standard *b*, the lever *c*, pivoted to said standard and in contact with said plunger, the sleeve *H*, movable on said lever, the measuring gate, the upright pivoted rod 5 *f*, and the rods *g* *h*, respectively connecting said rod *f* with the said sleeve and said gate, substantially as set forth.

In testimony whereof I affix my signature in presence of two witnesses.

ORLANDO FULLER BELCHER.
